ABDOMINAL BANDAGE

Lula Goforth, Denver, Colo.

Application March 8, 1946, Serial No. 653,048

3 Claims. (Cl. 128—96)

1

This invention relates generally to the class of surgery and pertains particularly to improvements in abdominal bandages and more particularly a device of this character designed for controlling or holding a hernia in place.

A particular object of the present invention is to provide an abdominal bandage or belt device which is designed particularly for maintaining a hernia pad in position and which is especially designed to perform this function and at the same time allow the wearer of the device all of the freedom of movement which he would have ordinarily and particularly allowing for the unrestricted movement of the back muscles.

Still another object of the invention is to provide a belt-like device for maintaining a hernia pad in position, which is so designed that it will not shift or ride up out of position.

A still further object of the invention is to provide a device of the character stated which is formed in a novel manner to give firm support across the abdomen and at the same time allow for free play of the muscles and unlimited freedom of movement in the back.

The invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modification mark no material departure from the salient features of the invention as expressed in the appended claims.

In the drawings—

Figure 1 is a view in front elevation of the hernia belt constituting the present invention, two of the straps of which are shown detached at their ends at the body of the belt, and portions of the body being broken away to show details of construction.

Figure 2 is a horizontal section taken substantially on the line 2—2 of the belt closed, as it appears in Figure 1.

Figure 3 is a detail section taken substantially on the line 3—3 of Figure 1.

Figure 4 is a back elevation of the belt closed, as shown in Figure 1, with portions broken away.

Figure 5 is a sectional view taken substantially on the line 5—5 of Figure 4.

Figure 6 is a sectional view taken substantially on the line 6—6 of Figure 4.

Figure 7 is a view looking at the front of the

2

belt opened out, with the ends of the shoulder straps and of the waist straps broken away.

Referring now more particularly to the drawings it will be seen particularly upon reference to Figure 7, that the body portion 10 of the belt is formed as a single panel of material substantially in the shape of a shield. The bottom edge of the panel 10, which, like the top edge is reinforced with a suitable binding tape 11, has the central downwardly directed point 12 and curves upwardly and outwardly from each side of this point as indicated at 13. This panel covers the major portion of the abdomen and along the vertical center of the body is secured the reinforcing tape 14 while at opposite sides of this tape are provided the pocket forming tapes 15 in which reinforcing stays 16 are retained.

As shown, the abdomen covering panel 10 tapers or is of gradually decreasing height toward its sides and each side is bifurcated to form the spaced continuing upper and lower waist encircling straps 17 and 18. These straps are suitably reinforced along their edges by binding tape, the top and bottom tapes 11 being continued along the outer edges of the adjacent upper and lower straps 17 and 18 while the inner or adjacent edges of the straps are reinforced by the binding tapes 19.

The ends of the binding tapes 19, as shown in Figure 7, and also in Figure 1, run into overlapping relation at 20 on the outer side or front of the panel 10, closely adjacent to the reinforcing stays 16.

The straps 17 and 18 which form integral continuations of the two sides of the abdomen covering panel or body portion 10, are of sufficient length to extend completely around the back of the wearer of the belt and substantially halfway across the front of the panel, as shown in Figure 1, from the side opposite to that from which the strap starts.

The front of the body panel 10 is provided with snap fastener buttons 21 in horizontally arranged pairs, as shown in Figure 1, to receive the snap button caps 22 carried by the straps 17 and 18. Each of the straps is secured by two snap buttons preferably but it will be readily apparent that any suitable number may be employed or any other suitable means may be made use of for securing the ends of the straps to the face of the body panel.

Secured to the top edge of the body panel is a bib 23 which is formed to have extending therefrom the two shoulder straps 24, which straps are of sufficient length to pass over the shoulders of

the wearer of the belt and down in the back to the uppermost waist straps 17 as shown in Figure 4. As is also shown in this figure and in Figure 6, the shoulder straps 24 are each formed to provide at its ends the loop or eye 25 through which a waist strap 17 is passed at the back of the belt.

One of the lower waist straps 18 has secured thereto the relatively long loop 26. This loop 26 is so placed on the strap 18 to which it is attached that it will be positioned at the center of the back of the wearer of the belt when the belt is put on and the straps 17 and 18 are fastened around the waist in crossed relation as shown in Figure 4. When the straps are secured around the waist in the crossed relation stated each of the straps 17 and the upper strap 18 is extended through the loop 26 which is disposed vertically as shown in Figure 4, the strap 18 to which the loop 26 is fastened, being the lowest in the group.

As is also clearly shown in Figure 4, one of the straps 17 passes through a loop or eye 25 of one of the crossed shoulder straps 24 while the other strap 17 passes through the loop 25 of the other shoulder strap below the first mentioned strap 17 to the outer or rear side thereof after passing through the large retaining loop 26. Thus both ends of the straps 17 may be brought out at the front of the panel and in alignment across the panel. The lower straps 18 are crossed in the same manner and are brought about for engagement at the front of the panel 10 adjacent to the bottom edge thereof, these lower straps being secured at their ends in downwardly converging relation as will be readily apparent upon reference to Figure 1.

It will be readily seen from the foregoing that when the belt is in position upon the wearer's body the pointed lower part of the abdomen covering panel 10 will be caused to conform to the curvature of the abdomen and thus a firm pressure may be applied to the entire surface thereof. At the back the shoulder straps connect with the top waist straps 17 and the entire group of straps is maintained against separation and in proper position by the centrally positioned, vertically arranged, long loop 26.

The present hernia belt was designed primarily for restraining a rupture or hernia in the region of the navel and accordingly there is shown particularly in Figures 2, 3, and 4, a pocket 27 which is positioned on the vertical center and adjacent to the bottom edge of the abdomen covering panel 10.

It will, of course, be understood that the invention is not limited to the disposition of the hernia pad pocket in the specific location shown but that the pocket may be disposed at any suitable position upon the inner or rear side of the panel 10 where necessary to apply pressure to the hernia.

The numeral 28 designates two tabs secured at opposite sides of the vertical center of the panel 10 and the bottom edge thereof. These are provided to facilitate the connection of the lower edge of the belt to a garment to assist in holding the belt in position as, for example, the tabs may be attached to stockings and thereby function as supporters or, in the case of using the belt upon an infant the tabs may be secured to the diaper.

As will be readily apparent upon reference to Figure 4 of the drawings, the loop 26 in the back of the belt holds the straps 17 and 18 and prevents such straps from crawling up or down, thereby holding the entire garment in place.

While the present improved hernia belt or bandage as here illustrated is designed for umbilical hernias, by changing the position of the hernia pad pocket it may be effectively used for retaining ventral, inguinal and femoral hernias.

The belt is so constructed as to hold the entire abdominal wall firmly, but the straps allow perfect freedom of the muscles of the sides and the back without disturbing abdominal firmness.

I claim:

1. A body belt of the character described, comprising a panel of fabric material adapted to extend across and cover the major portion of the abdomen between the hips of the wearer, a pair of strap members extending laterally from each side of the panel, each of said strap members being of sufficient length to extend across the back of the wearer of the belt and at least halfway across the front of the panel, means for attaching the ends of the straps to the front of the panel, and a loop carried by one of the straps in a position for location at the central part of the back of the wearer of the belt and adapted to have the other straps pass there through for coupling the straps together at the back of the wearer.

2. A body belt of the character described in claim 1, with shoulder straps each connected at one end to the top of the panel, and a loop forming a terminus for the other end of each shoulder strap adapted to receive one of the first mentioned straps at the back of the wearer, the loop carried by the said one of the straps being positioned between said terminal loops.

3. A belt structure of the character described, comprising a fabric panel designed to extend across the abdomen between the hips of the wearer, a pair of relatively long straps extending from each side of the panel, the straps being of a length whereby those of one pair may be carried around the back of the wearer in crossed relation with the straps of the other pair and the ends of the pairs of straps may be disposed across the front of the panel, means for attaching the ends of the straps to the front of the panel, one of said straps of one pair having secured thereto a relatively long loop designed to have all of the other straps extended therethrough, said loop being attached to the said one of the straps at a point where it will position at the center of the back of the wearer of the belt, a pair of shoulder straps attached to the top of the panel, a loop formed at the free end of each shoulder strap adapted to receive one of the first mentioned straps, and means upon the inner side of the fabric panel for supporting a hernia pad.

LULA GOFORTH.
